DESIGN FOR A SECTIONAL DISPLAY COUNTER

Neel S. Irwin, Cleveland Heights, Ohio

Application October 5, 1944, Serial No. 115,878

Term of patent 14 years

(CL. D80—9)

To all whom it may concern:

Be it known that I, Neel S. Irwin, a citizen of the United States, and a resident of Cleveland Heights, in the county of Cuyahoga and State of Ohio, have invented a new, original, and ornamental Design for Sectional Display Counter, of which the following is a specification, reference being had to the accompanying drawing, forming a part thereof.

The figure is a perspective view of a sectional display counter, showing my new design.

I claim:

The ornamental design for a sectional display counter, as shown.

NEEL S. IRWIN.
